UNITED STATES PATENT OFFICE.

ALBERT F. BEMIS, OF NEWTON, MASSACHUSETTS, ASSIGNOR TO BEMIS INDUSTRIES, INC., OF BOSTON, MASSACHUSETTS, A CORPORATION OF DELAWARE.

BUILDING CONSTRUCTION.

Application filed December 2, 1925. Serial No. 72,673.

This invention relates to building constructions such as dwelling houses, office buildings, factories, warehouses, garages, etc., and more particularly to initial formative processes for fabricating such structures.

Objects of this invention are to provide a construction in which the component parts may be quickly and easily assembled with a minimum amount of labor especially so that the parts may be prepared in advance and quickly assembled in situ to form the primary outline of a building. This type of construction is designed to permit economy in time, money, labor, and materials and to allow the employment of a large proportion of unskilled labor.

A salient feature of this invention is the use of standardized columnar units, which are preferably tubular and which may be combined with other standardized units to form the primary outline of a concrete building in such a way that the amount of skilled labor required to build temporary wooden forms for pouring concrete is greatly reduced. These units may form the basis for the formation of the various walls of the building, such as the vertical side walls, or partitions, inclined roof surfaces or the like, or horizontal floors and roofs. Wooden studding and framing may be practically dispensed with and the standardized units are of a type that lend themselves readily to a fireproof construction. The use of tubular units insures a considerable air space in the walls, thus providing heat insulation and affording an opportunity for the installation of electric wires, water pipes and other connections. Furthermore this construction forms a firm backing for an outer layer of cement applied by a cement gun or for other means.

The essential idea of my invention is applicable to a wide range of variations, for example reinforcing means can readily be arranged in almost any desired manner, while cement can be poured into a varying number of tubular members to form solid columnar units as conditions require, and the units themselves may be arranged at varying distances from one another to give different wall sections. These and many other advantages will appear to those skilled in the art, upon a reading of the following description.

In the drawings:

55

Fig. 1 is a vertical section through a side wall and portions of the floors and roof of a building;

60

Fig. 2 is a perspective view of a foundation;

Fig. 3 is a detail view;

Fig. 4 is a sectional view;

Fig. 5 is a section on line 5—5 of Fig. 1;

Fig. 6 is a section on line 6—6 of Fig. 4;

Fig. 7 is a similar view of another embodiment of the invention;

65

Fig. 8 is a section on line 8—8 of Fig. 4;

Fig. 9 is a detail view;

Fig. 10 is a broken detail view;

Fig. 11 is a view similar to Fig. 6 of another form of the invention;

70

Fig. 12 is a similar view of another form of the invention;

Fig. 13 is a sectional view corresponding to Fig. 5, but illustrating another embodiment of the invention.

75

Fig. 14 is an end view of a unit.

The particular embodiment of my invention shown for illustration utilizes similar columnar units 1 which may be of any form, but which are preferably tubular, and are shown as being of cylindrical form for purposes of convenient illustration and description. The walls of these units are preferably of light cementitious material such as gypsum, although fiber board, sheet metal or any other suitable substance may be used.

80

To form an improved building according to my invention a concrete foundation 2 is first poured with its upper surface recessed, as indicated by numeral 3, to engage the lower ends of the tubular units 1 and to hold them against transverse movement. A shallow longitudinal recess may be formed to engage a series of units as indicated in Figure 2, or before the cement is poured cylindrical forms or cups 4 may be located at the position where depressions are to be formed. Several of the cups 4 are preferably formed into a unit in order to insure ready alinement. After the foundation has hardened the cups 4 may be removed or they may preferably be left to line the depressions 3 as shown in Fig. 3. The units 1 are then disposed in a juxtaposed upright position with their lower ends in the recessed portion 3. After a series of units are set up, rangers 6 resting upon the foundation 2 are clamped

85

90

95

100

105

about their lower ends. These rangers 6 may be of wood but are preferably of a light cementitious material such as gypsum, having inner surfaces shaped with curved 6 grooves 8 to fit around portions of the cylindrical outer walls of the units 1. Any suitable means such as bolts 9, passing between the units, may be used to draw the rangers together. Rangers 7 of similar form but of substantially less depth are next clamped about the upper ends of the units 1 thereby drawing these portions into accurate alignment, the respective upper surfaces of the rangers 7 and the tubular units 1 having substantially the same level. While either the rangers 6 or the recessed portion 3 may be omitted, their use insures a more solid and accurate construction and facilitates the application of the upper rangers 7.

20 Layers 10 of cementitious material may be placed about the upright units 1, forming flat inner and outer walls and filling the irregularities and spaces between the various members. This operation may be performed in any well known manner, but it offers an especially advantageous opportunity for the use of the cement gun. As shown in Fig. 2, the cement 10 preferably has sufficient thickness to conceal the outer surfaces of 25 rangers 6 and 7 although these surfaces may substantially coincide with the surfaces of the cement wall, whenever the appearance of such an arrangement would not be objectionable.

30 Instead of a monolithic mass of material, slabs of cementitious material, wood, fiber board or the like may be placed against the units 1 to form a wall. One embodiment of such a construction is illustrated in Fig. 40 13 wherein the slabs 30 are fitted against the opposite sides of units 1. Pairs of these slabs are connected to each other by rods 31, which are pivotally secured to eyes 32 or otherwise fastened to the midportions of 45 the slabs, and are designed to extend between two adjoining columnar units. The corresponding inner and outer slabs 30 may be manufactured and assembled in a unit with the connecting rods 31, so that in order to 50 form the wall it is only necessary to place one of these units against a tubular unit and then another tubular unit against one of these units in alternating order, with the rods 31 extending between the tubular units.

55 The walls of the first story having been constructed in such a manner, if it is desired to apply a flat roof or a floor for a second story, planks 14 may be located with their ends resting upon the inner margins of the 60 side walls. The planks 14 may be of any suitable light cementitious material such as gypsum or of fibrous material such as wood, preferable the former. These members are of a sufficient length to span the distance 65 between the opposite walls of a room or

building and when necessary their centers may be supported by temporary struts in any well known manner, and of course, if desired, their ends may be similarly braced. Above each plank 14 is placed a tubular unit 70 1^a similar to the units 1. These units preferably do not have as great a length as the planks 14, but terminate substantially in a line with the inner surface of the side walls as shown at 16 of Fig. 8. The unit 1^a may 75 be held upon the planks 14 by any suitable method. I have shown the shallow grooves 17 in the upper surface of the planks 14 shaped to fit the section of the curved wall of the units 1^a with the wires 45 extending 80 over the unit and secured to the plank at either side, but these members may also be bolted together as indicated in Fig. 7 or other fastening means may be used. Each member 1^a is preferably assembled in a unit 85 with the corresponding plank before being placed upon the side walls, although the mode of assembly may be varied to meet the individual requirements. An assembly of this type is shown more particularly in 90 Fig. 14.

Capping strips 19 of any suitable material (Fig. 10) are placed over the upper ends of wall units 1, openings 20 of these strips registering with the hollow interiors of certain columns 1, while cylindrical caps 15 are similarly used to cover some or all of the ends of units 1^a. When necessary reinforcing rods 18 are situated between the units 1^a, and concrete is then placed around these members and over the capping strips 19, forming a floor 22 with integral girts 24 above the side walls as well as columns 23 100 registering with the openings 20 in the capping strip. These various parts are thus 105 formed into practically a monolithic structure. This operation may be performed by pouring cementitious material into a form built up to outline the outer surfaces of beams 24, or the cement gun may be used for 110 this purpose. If desired a suitable covering may be applied to the planks 14 to form a finish for the ceiling.

A monolithic floor or roof may be formed about the units 1^a in various other ways. For example a temporary form may be substituted for the planks 14 (Fig. 11), tubular units placed thereon and cement poured over them and allowed to harden, the temporary form then being removed. A layer of plaster 38 may then be applied to the lower surface of the horizontal wall if desired. In another embodiment of my invention shown in Fig. 12 either a temporary form of this type or planks 14 may be utilized, being first covered with a layer of cementitious material upon which are laid a series of tubular units, a second layer of cement then covering the units so that they are entirely 120 surrounded by a cementitious mass.

If it is desired to add another story, a recessed portion 3, similar to that formed in the foundation 2, is formed in the upper surface of girt 24 and units 1 are engaged in this recessed portion as has been previously described. In a like manner any desired number of stories may be erected.

In order to erect a pitched roof of the form shown in Fig. 2 the planks and units 1^a in 10 the upper floor are installed in the manner that has already been described. At the ends of the units, girts 26 are formed to have the shape indicated in Fig. 2 with an upper inclined surface approximately at right angles to the inclination of the proposed roof. A recessed portion 3^b may be formed in this surface as shown or it may be omitted. An auxiliary range member 34 having an inclined upper surface is placed above 20 each end of the upper floor 27. The prepared key beam 33 is located below the ridge of the roof with inclined upper surfaces aligned with the similar portions of range members 34 at either side of the building. 25 The planks 14^b which are like the floor planks 14, previously described, can then be laid upon these inclined surfaces preferably with the lower ends of the planks abutting the floor 27. The auxiliary range member 34 30 and the ridge beam 33 are preferably standardized units of material similar to that used for the rangers 6 and 7. Tubular units 1^b similar to those previously described are either engaged in the recessed portion 35 3^b of girt 26 or are set with their ends upon the inclined surface of that member, as the case may be, being assembled with planks 14^b in any of the ways previously described with reference to the floor construction. 40 Concrete is then applied over and between the units 1^b forming a cementitious layer between the tubular units and a flat surface for the roof which may be covered by suitable roofing material if desired.

45 The mode of construction disclosed in Fig. 13 may also be used for the fabrication of roofs. For example, a pitched roof may be erected with the slabs and tubular members extending crosswise or lengthwise, or a flat 50 roof may be built in a similar manner.

Many alternative modes of construction disclosed in my copending applications, No. 33,173, filed September 13, 1925 or Nos. 55 72,674, 72,675, 72,676 and 72,678, filed of even date herewith may be employed in conjunction with various features of the present invention—e. g. projecting members instead of recesses may telescope with the ends of the tubular units or key members may be engaged in slots to secure the units to the adjacent structure.

I claim:

1. In a building construction a base member having a recessed portion, a series of columnar units having their lower ends en-

gaged in said recessed portion, and members clamping the columnar units in alinement.

2. In a building construction, a series of alined columnar units having their ends supported upon a common base member and 70 elongate alining members secured upon the opposite sides of the columnar units.

3. In a building construction, a series of alined columnar units having their ends supported upon a common base member, an alining member secured to the upper portions of the units, and a layer of cementitious material covering said units and said alining member. 75

4. In a building construction, a base member having a recessed portion, a series of columnar units having their lower ends engaged in said recessed portion, and members clamping the upper portions of the units in alinement. 80

5. In a building construction a base member having a recessed portion, a series of columnar units having their lower ends engaged in said recessed portion, members clamping the lower portions of the columnar 90 units and other members clamping the upper portions of the columnar units.

6. In a building construction, a base member having a recessed portion, a series of columnar units having their lower ends engaged in said recessed portion, members clamping the columnar units in alinement and a layer of cementitious material covering the units and clamping members. 95

7. A building construction comprising a series of vertical juxtaposed wall elements, a girt extending along the ends of the wall elements, and another series of juxtaposed elements extending from the girt at an angle to the plane of the wall, and substantially monolithic extensions of said girt extending between said wall elements and between said elements which are located at an angle thereto. 100

8. A building construction comprising a series of vertical juxtaposed wall elements, a girt extending along the ends of the wall elements, and another series of juxtaposed elements extending from the girt at an angle to the plane of the wall, and substantially monolithic extensions of said girt extending between said wall elements and between said elements which are located at an angle to said elements and forming a continuous cementitious layer above the last named elements. 115

9. A building construction comprising a row of juxtaposed tubular wall elements, a girt extending along the ends of the wall elements and another series of juxtaposed elements extending from the girt at an angle to the plane of the wall elements, said girt consisting of cementitious material and being provided with substantially integral extensions extending into tubular body por- 120 125 130

tions of certain of the wall elements and being provided with other extensions extending in spaces between the elements which are located at an angle to the wall elements.

5 10. A building construction comprising a series of elongate, juxtaposed wall elements, a girt located at the adjoining ends of the wall elements, a layer of cementitious material covering the outer surface of the wall elements, said layer of cementitious material and said girt being substantially integral.

11. A building construction comprising a series of elongate, juxtaposed wall elements and a series of elongate juxtaposed floor elements, a girt located at the adjoining ends of the wall and floor elements, a layer of cementitious material covering the outer surfaces of the wall elements, and a layer of cementitious material overlying the floor elements, said layers of cementitious material

and said girt being substantially integral.

12. A building construction comprising a series of juxtaposed, elongate, vertical wall elements, a girt at the upper end of the wall elements, a series of juxtaposed floor elements extending from the girt, said girt consisting of cementitious material and being provided with integral extensions lying between certain of the floor elements and reinforcing members imbedded in said extensions and having their ends bound in said girt.

13. In a building construction, a base member, a series of columnar units having their lower ends in interfitting engagement with said base member, and members clamping the upper portions of the units in alignment.

Signed by me at Boston, Massachusetts,
this 30th day of October 1925.

ALBERT F. BEMIS.
